(74) *Attorney, Agent, or Firm* — Sughrue Mion, PLLC

CLAIM

The ornamental design for a portable wireless telephone, as shown and described.

DESCRIPTION

FIG. 1 is a Front view thereof;

FIG. 2 is a Rear view thereof;

FIG. 3 is a Left Side view thereof;

FIG. 4 is a Right Side view thereof;

FIG. 5 is a Top Plan view thereof;

FIG. 6 is a Bottom Plan view thereof;

FIG. 7 is a Perspective View of the open state thereof;

FIG. 8 is a Front View of the open state thereof;

FIG. 9 is a Rear View of the open state thereof;

FIG. 10 is a Rear Perspective View of the open state thereof;

FIG. 11 is a Right Side View of the open state thereof;

FIG. 12 is a Left Side View of the open state thereof;

FIG. 13 is a Top Plan View of the open state thereof; and,

FIG. 14 is a Bottom Plan View of the open state thereof.
